BOBBY-PIN HOLDER AND OPENER

Carl G. Skinner, Bell, Calif.

Application November 3, 1947, Serial No. 783,730

13 Claims. (Cl. 132—1)

1 The present invention relates to an improved bobby-pin holder and opener, particularly for use by ladies' hairdressers and beauty operators for the purpose of supporting an ample number of bobby-pins so that they are conveniently accessible for carrying out the hairdressing operation.

An object of the invention is to provide a bobby-pin holder adapted for application to the wrist or arm of the operator, and to this end it is proposed to provide a split spring band member which may be readily and firmly engaged upon either the left arm or the right arm, depending upon whether the operator is right or left-handed, and further to provide a pin supporting band, supported upon the wrist engaging band in spaced parallel relation thereto, for the purpose of supporting the bobby-pins out of contact with the skin of the wearer and in position to be easily removed.

Another object is to provide a holder having a wrist engaging band and a pin supporting band in spaced parallel relation thereto, and which is adapted to be freely expanded for engagement upon the wrist or arm without changing the parallel relation of the two bands, and without disturbing the positions of the bobby-pins supported upon the holder.

Another object is to provide pin opening means carried by the holder, whereby the legs of the pins are spread as they are removed from the holder so that they are in proper shape for convenient insertion in the hair.

With the above and other objects in view, an embodiment of the invention is shown in the accompanying drawings, and this embodiment will be hereinafter more fully described with reference thereto, and the invention will be finally pointed out in the claims.

In the drawings—

Fig. 1 is a side elevation of the bobby-pin holder, according to one illustrated exemplary embodiment of the invention, several bobby-pins being shown engaged on one side thereof.

Fig. 2 is a top plan view, and showing the manner in which a bobby-pin is engaged with the opening means.

Fig. 3 is an end elevation of the holder, as seen in Fig. 1.

Fig. 4 is a transverse sectional view, taken along the line 4—4 of Fig. 3.

Fig. 5 shows the holder, as worn on the left wrist of the operator, the opening means being disposed inwardly for convenient accessibility by the right hand of the operator.

2 Fig. 6 is a side elevation of a modified form of bobby-pin holder.

Fig. 7 is a top plan view thereof.

Fig. 8 is an end elevation.

Fig. 9 is a transverse sectional view, taken along the line 9—9 of Fig. 8, showing the manner in which a pin is grasped preparatory to removal.

Fig. 10 shows the removed pin as held in spread position.

Similar reference characters indicate corresponding parts throughout the several figures of the drawings.

Referring to the drawings, the bobby-pin holder and opener, according to the exemplary embodiment of the invention, illustrated in Figs. 1 to 5, comprises an inner wrist engaging band 10 formed of suitable springy material, which may, for instance, be plastic material, springy metal, or the like, and which is open at one end for engagement upon the wrist or arm by expanding the band, the terminals of the two legs of the band being outwardly curved, as at 11—11, for easy engagement and disengagement.

An outer bobby-pin supporting band 12, generally conforming to the shape of the band 10 is supported thereon in spaced parallel relation, and for this purpose is provided internally at its closed end with a rib-like separator portion 13 engaged with the outer surface of the member 10 and secured thereto by rivets 14—14. The terminals of the two legs of the band 12 are curved inwardly, as at 15—15, into engagement with the band 10 at points in upwardly spaced relation to the curved terminal ends 11, and, in co-operation with the separator portion 13, support the band 12 in spaced parallel relation to the band 10. The terminals 15 have sliding engagement with the band 10, and consequently permit the two bands to be freely expanded and contracted during engagement or disengagement of the holder with the arm, and without substantial change in the spaced parallel relation of the bands to each other. The curved terminal ends 11 will act as stops for the terminal ends 15, and thus limit the extent to which the holder may be opened, thereby preventing excessive expansion and strain thereon.

The pin supporting band 12 is substantially narrower than the wrist engaging band 10, and being set off from it effectually prevents the bobby-pins from contacting the skin of the wearer. At the same time ample space is provided for gripping and removing the pins.

Upon the closed end of the pin supporting band

12, and preferably between the rivets 14-14, there is provided a pin opening projection 16 having pointed wedge portions at each end, so that a pin may be readily engaged therewith in either direction and conveniently forced to open position where it can then be held by the thumb and forefinger preparatory to insertion in the hair.

In operation, a suitable number of the bobby-pins are engaged upon the band 12 at one or both sides, with one leg of each pin disposed in the space between the two bands so that it may be easily removed without contact with the wrist engaging band or the skin of the wearer. In engaging the pins upon the band 12, they will tend to automatically assume transverse positions in parallel relation to each other because of the curvature of the band 12. In the case of engaging pins upon the holder while it is being worn, the inner band 10 effectually guards the skin against contact by the point ends of the pins.

The pin supporting band 12 may be constructed of the same material as the wrist engaging band 10, that is, of springy plastic, metal, or other suitable material, and the separator portion 13 and projection 16 may be either integrally formed therewith, or these portions may be separately formed parts suitably secured to the holder.

In Figs. 6 to 10, there is illustrated a modified form of the invention wherein the bobby-pin opening projection 16 as employed in the modification shown in Figs. 1 to 5 is dispensed with. For the purpose of opening the bobby-pin, preparatory to insertion in the hair, the outer bobby-pin supporting band 12 is provided at one of its curved edges with an inwardly inclined flange 17, the edge of which is spaced from the wrist engaging band 10 to provide a clearance space in which one leg of the bobby-pin is engaged, so that, through the camming action of the flange, this leg is spread to a substantial degree with respect to the other leg. In operation, the holder is preferably placed upon the wrist with the flange 17 disposed inwardly. In order to remove the bobby-pin, it is grasped by the thumb and forefinger, as indicated in Fig. 9, so that the outwardly disposed leg of the bobby-pin is grasped at its end just beyond the flange 17 with the ends of the thumb and forefinger substantially abutting the other leg of the bobby-pin. With the thumb and forefinger still grasped in this position, the bobby-pin is removed in the direction as indicated by the arrow, the ends of the thumb and forefinger moving away from the inner leg of the bobby-pin and sliding over the outer surface of the band 12. As soon as the thumb and forefinger move beyond the edge of the band 12, the inner leg of the bobby-pin springs back into engagement with the ends of the thumb and forefinger, as indicated in Fig. 10, the bobby-pin being thus held in its proper open position for convenient insertion into the hair.

I have illustrated and described a preferred and satisfactory embodiment of the invention, but it will be understood that changes may be made therein, within the spirit and scope thereof, as defined in the appended claims.

What is claimed is:

1. A holder for bobby-pins or the like, comprising a stiff but springy wrist engaging band member, and a stiff but springy pin supporting member carried by said band member including a band portion disposed in outwardly spaced relation to said wrist engaging band member and adapted to

be embraced frictionally by a plurality of resilient bobby-pins or the like, and a separator portion fixed between said members to support and space said pin supporting member relatively to said band member.

2. A holder for bobby-pins or the like, comprising a substantially C-shaped stiff but springy wrist engaging band member, and a substantially C-shaped stiff but springy pin supporting member carried by said band member disposed in outwardly spaced parallel relation to said wrist engaging band member and adapted to be embraced frictionally by a plurality of resilient bobby-pins or the like, transversely engaged therewith, and a separator portion connecting the intermediate portions of said members, said pin supporting member having inwardly directed terminal end portions engaged with said band member.

3. A holder for bobby-pins or the like, comprising a wrist engaging band member, and a pin supporting member carried by said band member including a band portion disposed in outwardly spaced parallel relation to said wrist engaging band member and adapted to be embraced frictionally by a plurality of resilient bobby-pins or the like, at least one circumferential edge of said band member being outwardly offset relative to a circumferential edge of said band portion.

4. A holder for bobby-pins or the like, comprising a wrist engaging band member, and a pin supporting member carried by said band member including a band portion disposed in outwardly spaced parallel relation to said wrist engaging band member and adapted to be embraced frictionally by a plurality of resilient bobby-pins or the like, the circumferential edges of said band member being outwardly offset relative to the circumferential edges of said band portion.

5. A holder for bobby-pins or the like, comprising an inner wrist engaging spring band member of substantially C-shape, an outer pin supporting spring band member of substantially C-shape disposed in outwardly spaced parallel relation to said wrist engaging band member, and adapted to be embraced frictionally by a plurality of resilient bobby-pins, or the like, and means connecting said band members together.

6. A holder for bobby-pins or the like, comprising an inner wrist engaging spring band member of substantially C-shape, an outer pin supporting spring band member of substantially C-shape disposed in outwardly spaced parallel relation to said wrist engaging band member, and adapted to be embraced frictionally by a plurality of resilient bobby-pins or the like, a separator portion connecting the intermediate portions of said inner and outer band members, said outer band member having inwardly directed terminal end portions slidably engaged with said inner band member in spaced relation to the terminal ends thereof.

7. A holder for bobby-pins or the like, comprising an inner wrist engaging spring band member of substantially C-shape, an outer pin supporting spring band member of substantially C-shape disposed in outwardly spaced parallel relation to said wrist engaging band member, and adapted to be embraced frictionally by a plurality of resilient bobby-pins or the like, a separator portion connecting the intermediate portions of said inner and outer band members, said outer band member having inwardly directed terminal end portions slidably engaged with said inner band member in spaced relation to the terminal ends thereof, the terminal ends of said inner band member being

outwardly directed and constituting limit stops for said terminal ends of said outer band member.

8. A holder for bobby-pins or the like, comprising a wrist engaging band member, and a pin supporting member carried by said band member including a band portion disposed in spaced relation to said wrist engaging band member and adapted to be embraced frictionally by a plurality of resilient bobby-pins or the like, and pin opening wedge means carried by said band portion.

9. A holder for bobby-pins or the like, comprising an inner wrist engaging spring band member of substantially C-shape, an outer pin supporting spring band member of substantially C-shape and disposed in outwardly spaced parallel relation to said wrist engaging band member, and adapted to be embraced frictionally by a plurality of resilient bobby-pins or the like, means connecting said band members together, and a pin opening wedge member carried upon the intermediate portion of said outer band member.

10. A holder for bobby-pins or the like, comprising an inner wrist engaging spring band member of substantially C-shape, an outer pin supporting spring band member of substantially C-shape and disposed in outwardly spaced parallel relation to said wrist engaging band member, and adapted to be embraced frictionally by a plurality of resilient bobby-pins or the like, means connecting said band members together, and a pin opening wedge member carried upon the intermediate portion of said outer band member, and having oppositely extending wedge portions.

11. A holder for bobby-pins or the like, comprising a wrist engaging band member, and a pin supporting member carried by said band member including a band portion disposed in spaced rela-

tion to said wrist engaging band member and adapted to be embraced frictionally by a plurality of resilient bobby-pins or the like, and projecting cam means on said band portion adapted to spread the side legs of said pins as they are engaged with said band portion.

12. A holder for bobby-pins or the like, comprising a wrist engaging band member, and a pin supporting member carried by said band member including a band portion disposed in spaced relation to said wrist engaging band member and adapted to be embraced frictionally by a plurality of resilient bobby-pins or the like, and cam means on said band portion projecting inwardly toward said band member and spaced therefrom adapted to spread the side legs of said pins as they are engaged with said band portion.

13. A holder for bobby-pins or the like, comprising a wrist engaging band member, and a pin supporting member carried by said band member including a band portion disposed in spaced relation to said wrist engaging band member and adapted to be embraced frictionally by a plurality of resilient bobby-pins or the like, and a cam flange projecting inwardly from one edge of said band portion and spaced from said band member adapted to spread the side legs of said pins as they are engaged with said band portion.
